UNITED STATES PATENT OFFICE.

CLINTON M. WOLFE, OF COEBURN, VIRGINIA, ASSIGNOR OF ONE-HALF TO CHARLES O. RAMSEY, OF COEBURN, VIRGINIA.

SPOOL-HOLDER.

1,273,971.

Specification of Letters Patent. Patented July 30, 1918.

Application filed March 30, 1918. Serial No. 225,616.

To all whom it may concern:

Be it known that I, CLINTON M. WOLFE, a citizen of the United States, residing at Coeburn, in the county of Wise and State 5 of Virginia, have invented certain new and useful Improvements in Spool-Holders, of which the following is a specification.

The present invention relates to improvements in spool holders, especially adapted 10 for use in holding spools of thread, while crocheting or knitting, and made of a single piece of wire, bent and fashioned to proper shape for the purpose.

The primary object of the invention is 15 the provision of a device of this character which is comparatively inexpensive in cost of production, simple in construction, and efficient in performing the functions for which it is intended.

20 The invention consists in certain novel combinations and arrangements of parts involving the one-piece holder and especially in connection with the resilient supporting bar for the spool and the means 25 for supporting this bar.

In the accompanying drawings one complete example of the physical embodiment of the invention is illustrated constructed and arranged according to the best mode 30 I have so far devised for the practical application of the principles of the invention.

Figure 1 is a top plan view of the spool 35 holder with the spool supported thereon.

Fig. 2 is a front elevation of the device.

Fig. 3 is a side elevation.

Fig. 4 is a side elevation view from the side opposite that of Fig. 3.

In the preferred embodiment of the invention the holder is made up of a single 40 piece of wire, and is formed with a body or basket portion involving the use of the three curved bars 1, 2, 3, that are arranged in vertical positions and parallel with each other, and the two outside bars 1 and 2 45 are fashioned with a rear arch bar 4 rising above the body of the supporter, while the intermediate bar 2 merges into a center upright bar 5, the arch bar and center upright bar being arranged in a knot 6 from which 50 the end 7 is bent into vertical position and pointed at its extremity to form a pin for attachment of the device to the dress or other object. Across the front of the body of the support, a front horizontal bar 8 ex-

tends, and its juncture with the three 55 curved guard bars 1, 2, 3, in each instance is formed as a knot 9, and the same numeral is used to indicate other joints or knots throughout the device. The body of the device is completed with the addition of the 60 two side bars which extend horizontally from front to rear and are continuations of the curved guard bars 1 and 3 respectively. One of these side bars is of rigid construction and embodies the single strand 65 10 extending its full length, while an additional strand 11 extends from rear to the axial center of the device thus strengthening and rendering more rigid this side bar. The spool bar 12 which supports the spool 70 13, is resilient and projects from this side bar comprising the reinforced parts described, extending across the length of the basket and is adapted to catch in the opposite side bar of the basket. This second 75 bar is fashioned with a double portion 14, in which the wire is bent upon itself, and a double portion 15, and between these two double bars or sections, a slot 12' is provided for the spool bar to be caught in. 80 At the front these double bar sections merge into the single strands 16 and 17 and are formed into a knot 9. An eyelet 18 is formed in the curved bar 2 through which the thread may be introduced and fed as 85 the thread is used.

From this description it will be evident that I have provided a supporting device that is rigid and well braced and connected, and provided with the resilient bar 12 and 90 an additional resilient member is provided in the portion 14 of the side bar which forms a tongue for the bar 12 whose resiliency holds the spool bar in place.

In using the device it will readily be 95 seen that the spool bar 12, because of its resiliency, may be bent in almost any direction from its joint 9 with the side bar 10-11, and thus, after the spool has been slipped over the free end of the spool bar, 100 the end of the bar is slipped under the resilient tongue 14 of the side bar and the end of the bar is then permitted to return, because of its resiliency or elasticity, to the position indicated in Fig. 4, or Fig. 1. 105 In taking off the spool, the end of the spool bar 12 is swung to the rear in Fig. 4 until it is freed from the tongue 14 and then the

spool and bar are raised, and the spool removed from the bar.

Claim:

A spool holder of a single piece of wire comprising three curved body bars one of which is formed with an eyelet, a front bar, the two outside bars merging into a rear arch bar, the intermediate curved bar secured to the arch bar and a pin projecting

from the junction of these parts, said body 10 having a rigid side bar, a resilient spool supporting bar projecting therefrom, and a second side bar fashioned with a slot for the spool supporting bar and formed with a resilient tongue, as described. 15

In testimony whereof I affix my signature.

CLINTON M. WOLFE.
